CLAIM

The ornamental design for fishing pliers as shown and described.

DESCRIPTION

FIG. 1 is a perspective view of fishing pliers showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the fishing pliers that form no part of the claimed design. The unshaded surfaces between the broken and solid lines in the drawings form no part of the claim.

1 Claim, 8 Drawing Sheets
